UNITED STATES PATENT OFFICE.

HUGO H. YOUNG, OF LOUDONVILLE, OHIO.

DESIGN FOR A MOVABLE HOLDER FOR BOOKS OR THE LIKE.

52,904.

Specification for Design.

Patented Jan. 14, 1919.

Application filed October 21, 1918. Serial No. 259,139. Term of patent 14 years.

To all whom it may concern:

Be it known that I, HUGO H. YOUNG, residing at Loudonville, in the county of Ashland and State of Ohio, a citizen of the United States of America, have invented a new, original, and ornamental Design for a Movable Holder for Books or the like, of which the following is a specification, reference being had to the accompanying drawing, forming a part thereof.

The figure represents a perspective view of the holder.

I claim:

The ornamental design for a movable holder for books or the like as shown.

HUGO H. YOUNG.

In the presence of—

VERA ZIMMERMAN,
MARCELLA YUNCKER.
